UNITED STATES PATENT OFFICE.

FRANK LANTIERI AND GABRIEL LANTIERI, OF NEWARK, NEW JERSEY.

HAIR-WAVING HEATER.

1,379,026.

Specification of Letters Patent. Patented May 24, 1921.

Application filed November 26, 1919. Serial No. 340,896.

To all whom it may concern:

Be it known that we, FRANK LANTIERI and GABRIEL LANTIERI, both residing at Newark, in the county of Essex and State of New Jersey, have invented certain new and useful Improvements in Hair-Waving Heaters, of which the following is a specification.

This invention relates to improvements in 10 heating devices, and more particularly to a new and improved electric heater adapted to be used in permanent hair waving.

One of the objects of the invention is to provide a heater of the above type, which 15 can be manufactured cheaply, and is exceedingly light in weight.

A further object of the invention is to provide a new and improved adjusting device, whereby two or more heaters may be 20 connected with a single lead or cable, and the relative position of the heaters conveniently adjusted to meet the requirements of waving hair upon the heat of a living subject.

25 Other objects and aims of the invention, more or less specific than those referred to above, will be in part obvious and in part pointed out in the course of the following description of the elements, combinations, 30 arrangements of parts and applications of principles, constituting the invention; and the scope of protection contemplated will be indicated in the appended claims.

In the accompanying drawings, wherein 35 we have shown a preferred form of embodiment of our invention:

Figure 1 is a longitudinal sectional view, taken through one of our improved heaters.

40 Fig. 2 is a transverse sectional view, taken on line 2—2 of Fig. 1, looking in the direction of the arrows; and

Fig. 3 is an elevational view, showing the 45 manner of connecting and adjusting a pair of heaters constructed in accordance with the present invention.

Referring now to the drawing, wherein 50 similar reference characters refer to similar parts through the views thereof, the reference numeral 1 denotes a cylindrical shell, preferably formed of metal, the ends of which are slightly flared, as at 2 and 3. Mounted upon one end of the cylindrical shell 1 is a ring 4, preferably formed of insulating material, such for instance as 55 pressed mica, asbestos, or other relatively solid insulating material.

It will be noted that the flared end 3 of the cylinder forms a shoulder, against which rests the said collar 4, so that the side surface thereof is flush with the end of the 60 cylinder.

Positioned upon the cylinder 1 is a layer 65 of insulating material 5, such as sheet mica, and about this layer of insulating material is wound the resistance wire 6, the ends of which are fastened to terminal members 7 and 8, comprising screws mounted in the inner wall of the ring or collar 4, openings 9 and 10 extending through the collar to accommodate the leading-in wires 11 and 12. 70

Mounted upon the ring or collar 4 is a shell 13, the same being positioned thereon with a relatively tight fit, and said shell, as it extends toward the opposite end of the heater, decreases in diameter as shown, until the inner end is substantially in contact with a sheet of mica 14 which provides an 75 insulating layer over the resistance wire 6.

The shell 13 is provided with a projection or flange 15, which extends endwise, parallel 80 with the heater, adjacent the cable 16, which carries the leading-in wires, which cable 16 is firmly bound to the flange 15, as by means of asbestos twine 17, which layer of asbestos twine is preferably solidified by insulating 85 cement, thus providing a handle by means of which the heater may be manipulated.

The mica sheet 14 is located exteriorly of the resistance wire 6, is covered by a layer 90 of insulating material 18, preferably asbestos twine, whereby the mica sheets and resistance wire are firmly fastened about the metallic shell 1, the ends of the mica sheets and the resistance wire extending in the space formed between the cylinder shell and 95 shell 13.

It will be noted that the layer of asbestos twine which may or may not be solidified as by means of the insulating cement, rests against the flange 2 of the cylinder 1 and engages the end 19 of the shell 13.

Thus it will be seen that the entire device is held together without the use of screws or rivets, making it very easy to assemble, and providing a structure in which the parts are 100 not liable to become loosened or separated.

Referring now to Fig. 3 of the drawings, it will be noted that cables 20 and 21 are branched off at 22 from a single cable 23, and that cables 20 and 21 are extended 110 through apertures, in an adjusting member 24, the same comprising a ball or spherically

formed block, having apertures in which the cables 20 and 21 fit with a slight frictional engagement, the cable 20 leading through the block 24, through the heater 25, and the cable 21 leading through said block to the heater 26. In giving to the hair a permanent waving form apparatus is customarily employed in practice having a number of suspended heaters, and it is necessary to adjust and arrange the positions of the heaters to relieve or prevent any straining or pulling of the hair of the subject. In applicants' construction, as fully illustrated in Fig. 3, conductors joined into a single cable are divided to form branches at the end of the cable, and the branches lead to a pair of heaters. The sliding block engages both branches and holds them together thus in effect making those branches shorter or longer as may be required. In other words, where several heaters are simultaneously in operation upon the hair of a subject, the members of each pair of heaters constructed in accordance with this invention are engaged by neighboring or adjacent strands of hair, and it is not desired that such associated heaters shall be inadvertently separated farther than intended. The heaters have substantially the same external appearance and when the hair-dresser is busy and attempts a rearrangement of the heaters hastily, it is an easy matter to mistake the members of one pair for individual members of another pair. If the members of any pair of heaters should be unintentionally and abruptly separated too far the hair would be violently pulled with disagreeable if not injurious consequences. By adjusting block 24 such a separation is prevented.

By means of this construction it will be noted that the number of cables leading from the connection or chandelier usually employed in this work is cut in half, the heaters are more easily manipulated, and moreover, by manipulating the cables 20 and 21 through their apertures in the block 24, the relative positions of the heaters 25 and 26 upon the head may be conveniently adjusted.

It will accordingly be seen that we have provided a construction well adapted to attain, among others, all the aims and objects above pointed out, in an exceedingly facile manner, the heaters are cheap to manufacture, easy of assemblage, in that no screws or rivets are required. Moreover, the construction is such that there is nothing about the heater to become disarranged, nor is there any likelihood of the interior heating or resistance wires becoming short-circuited, the parts being all positively held in fixed relation. The arrangement of the heaters in pairs is also convenient, as well as economical.

As many changes could be made in this

construction without departing from the scope of the following claims, it is intended that all matter contained in the above description or shown in the accompanying drawing shall be interpreted as illustrative only and not in a limiting sense. 70

Having thus described our invention what we claim as new and desire to secure by Letters Patent is:

1. In a device of the character described, 75 the combination with a hollow cylinder having flanged ends, of a collar of insulating material mounted upon the said cylinder and seated against one of the said flanges, layers of insulating material surrounding the said cylinder, a coil of resistance wire arranged between said layers of insulation, conductors passing through the said collar and connected with the said resistance wire, a cupped shell having its larger end encircling and in contact with the said collar, the said shell surrounding the said cylinder and layers of insulation and extending from the said collar for a part of the length of the cylinder, and asbestos twine binding encircling 85 the said cylinder and insulating layers between the end of the shell and the other flanged end of the cylinder whereby the insulation, coil, shell and the said collar are secured in place. 90

2. In a device of the class described, a hollow cylinder having flanged end portions, a collar of insulating material mounted upon said cylinder and seating against one of the flanges thereof, a plurality of layers 100 of insulating material positioned upon said cylinder, a coil of resistance wire positioned intermediate said layers of insulating material, leading-in wires extending through said collar, terminal members carried by 105 said collar and connected with said leading-in wires, said terminal members being also connected with said resistance wires, a shell mounted upon said collar, said collar extending rearwardly and inwardly and terminating adjacent the layer of insulating material covering said resistance wire, a covering of insulating material disposed about the outer layer of said last named insulating material and interposed between the 110 rear edge of said shell and the flanged portion of said cylinder, said shell being provided with a flange which extends beyond the first named end of the cylinder, a cable carrying the leading-in wires disposed adjacent said flange, and a covering of insulating material binding said cable and flange together. 115

3. The combination with a pair of heaters of the character and for the purpose described, of conductors united into a single cable having branches at its end, the said branches being connected with the said heaters, and a movable device engaging the said branches of the cable and holding them 125 130

together whereby the length of the said branches may be adjusted.

4. The combination with a pair of heaters of the character and for the purpose described, of conductors united into a single cable having branches at its end, the said branches being connected with the said heaters, and a sliding block having passages frictionally engaging the said branches of the 10 cable and holding them together whereby

the length of the said branches may be adjusted.

In testimony whereof we affix our signatures in the presence of two witnesses.
